L. R. ACCORNERO AND A. GAYDOU.
LANDING DEVICE FOR AEROPLANES.
APPLICATION FILED JULY 2, 1918.

1,312,507.

Patented Aug. 12, 1919.

UNITED STATES PATENT OFFICE.

LOUIS R. ACCORNERO AND ADOLPHE GAYDOU, OF NEW YORK, N. Y.

LANDING DEVICE FOR AEROPLANES.

1,312,507.

Specification of Letters Patent.

Patented Aug. 12, 1919.

Original application filed March 5, 1918, Serial No. 220,636. Divided and this application filed July 2, 1918. Serial No. 243,028.

To all whom it may concern:

Be it known that we, LOUIS R. ACCORNERO and ADOLPHE GAYDOU, citizens of the United States, residing at New York, in the county of New York and State of New York, have invented certain new and useful Improvements in Landing Devices for Aeroplanes, of which the following is a specification.

This invention relates to aeroplanes and constitutes a division of our copending application filed March 5, 1918, Serial No. 220,636.

The object of the present invention is to provide a novel landing means for an aeroplane and more particularly for an aeroplane of that type which are designed to ascend directly vertically from the starting position and to likewise descend vertically. Therefore, the chief object of the invention is to provide highly efficient shock absorbing means designed to cushion the aeroplane as it reaches the ground surface so that although the descent of the aeroplane may be rapid the passengers and equipment of the plane will not be subjected to injurious shock or jar as the aeroplane reaches the ground.

In the accompanying drawings:

Figure 1 is a view in elevation of the lower portion of the aeroplane of our invention, illustrating the landing device forming the subject of the present divisional invention;

Fig. 2 is a horizontal sectional view taken substantially on the line 2—2 of Fig. 1 and looking in a downward direction.

In the drawings the numeral 1 indicates in general the body of the aeroplane, the body comprising a number of cars 2 having bottoms 3. As before indicated, by suitable propeller mechanism, the aeroplane is to be caused to ascend directly vertically from a standing position and is adapted likewise to descend vertically, and in order, as before stated, to cushion the shock of descent of the plane as it reaches the ground, shock absorbing or cushioning devices are provided beneath the bottoms 3 of the several cars 2.

Each of the shock absorbing devices referred to above comprises a substantially rectangular frame 4 which constitutes a foot member, and legs which are indicated in general by the numeral 5 and which extend

upwardly from the respective foot members and are secured to the under sides of the bottoms of the respective cars 2. The legs 5 are preferably in the nature of coiled compression springs which are seated and secured at their lower ends in sockets 6 at the four corners of the respective feet 4, and the said legs, from the said sockets 6, are led upwardly along converging lines and secured together by suitable tie members, as indicated by the numeral 7, the upper ends of the legs being secured in suitable sockets 8 upon the under sides of the bottoms of the respective cars. Thus not only do the legs 5 serve to cushion the cars when the feet 4 strike the ground surface, due to the fact that they are in the nature of compression springs, but this cushioning and shock absorbing quality is greatly enhanced by reason of the fact that the legs 5 instead of extending vertically between the feet 4 and the floors of the respective cars, are twisted out of vertical alinement, as shown in the drawings, so that they are placed under torsional as well as under compressive stress upon impact of the feet with the ground surface.

It will also be understood from the foregoing that should the machine descend with a slight drift in any direction, the legs 5 by reason of their peculiar arrangement, will serve to bring the machine to an equilibrium much more quickly than if the said legs extended directly vertically.

Having thus described the invention, what is claimed as new is:

1. In an aeroplane, a body, and a cushioning means for the said body comprising an impact foot, and compression springs secured at their lower ends to the said foot and at their upper ends to the bottom of the body, the said springs being distorted out of vertical alinement. 95

2. In an aeroplane, a body, and a cushioning means for the said body comprising an impact foot, and compression springs secured at their lower ends to the said foot and at their upper ends to the bottom of the body, the said springs being distorted out of vertical alinement and adjacent springs being secured together at their relatively adjacent portions. 100

3. In an aeroplane, a body, and a cushioning means for the said body comprising an impact foot, and compression springs secured at their lower ends to the said foot
- 5 and at their upper ends to the bottom of the body, the said springs being distorted out of

vertical alinement, and tie members connecting adjacent ones of the springs.

In testimony whereof we affix our signatures.

LOUIS R. ACCORNERO. [L. S.]
ADOLPHE GAYDOU. [L. S.]
